GASEOUS ELECTRIC DISCHARGE METAL
VAPOR LAMP DEVICE

Willem Uyterhoeven, Cornelis Verburg, and
Martinus van Dam, Eindhoven, Netherlands,
assignors to General Electric Company, a
corporation of New York

Application September 18, 1934, Serial No. 744,470
In Germany September 29, 1933

1 Claim. (Cl. 176—124)

The present invention relates to gaseous electric discharge metal vapor lamp devices generally and more particularly the invention relates to circuits comprising such devices useful in illuminating outdoor areas.

The intensity of the light emitted by metal vapor lamps is affected by changes in current and vapor pressure. Changes in ambient temperature cause changes in the vapor pressure in the lamp and changes in the intensity of the light emitted by the lamps. When the current in the lamp is such that the heat of the discharge is sufficient with regard to a definite ambient temperature to develop a vapor pressure such that the lamp emits a maximum intensity of light a drop in ambient temperature causes a drop in vapor pressure and the lamp emits lower intensity light. An increase in ambient temperature also deleteriously affects the vapor pressure.

The object of the present invention is to provide a circuit comprising a plurality of metal vapor lamps whereby the influence of ambient temperature changes on the vapor pressure in the lamp and on the intensity of the light emitted thereby is eliminated. Another object of the invention is to provide means for maintaining a substantially constant vapor pressure in an electric discharge vapor lamp over a wide range of ambient temperatures. Still further objects and advantages attaching to the device and to its use and operation will be apparent to those skilled in the art from the following particular description.

The invention attains its object by connecting in the lamp circuit a regulating device which is controlled by the ambient temperature and which, when the ambient temperature drops, increases the voltage supplied to the lamps, or reduces a variable impedance which is connected in series with the lamps and which reduces the voltage or increases the impedance when the ambient temperature rises.

When the ambient temperature drops a stronger current is caused to pass through the lamps so that the increase in heat radiation of the lamps, caused by the drop in the ambient temperature, is compensated for by the increased heat developed by the discharge. In the same way the current strength is caused to be decreased when the ambient temperature increases. By the above mentioned means the advantage is gained that the vapor pressure in the discharge lamps in the circuit is independent of changes in the ambient temperature.

In the drawing accompanying and forming

part of this specification two embodiments of the invention are shown schematically in Figures 1 and 2.

The embodiment illustrated in Fig. 1 comprises a number of U-shaped, tubular, electric discharge lamps 1, each of which contains a rare gas, for instance neon, at a pressure of approximately 1 to 10 mm. of mercury, and a quantity of vaporizable metal, such as sodium, the vapor of which participates in the light emission of the discharge lamps when excited to luminescence by the passage of an electric discharge therethrough. A thermionic electrode is sealed into each end of said lamps 1. Further structural details of the discharge lamps are omitted as such details are well known and need not be described here since they are not essential for an understanding of the present invention.

The discharge lamps are connected to the secondary coils 2 of the transformers 3, the primary coils 4 of which are connected in series with each other and are connected with the secondary transformer coil 6 over an external impedance 5.

This transformer comprises a core 7 on which the primary coil 8 is mounted and said coil 8 is connected to the terminals of an alternating current source. This primary coil 8 has a fixed position on said core 7 while the secondary coil 6 is adjustable vertically and is hung on the balance 9 which is provided with a counter-weight 10. The arc shaped member 11 of this balance 9 is adjusted in such manner that the lever arm of the counter-weight 10 has different lengths for various positions of the balance 9. This shape of the member 11 is selected in order that, for all positions of the balance 9, the counter-weight 10 is in equilibrium with the inherent weight of the coil 6 and the attractive power between coils 6 and 8.

The movements of the balance 9, and therewith those of the coil 6, are controlled solely by the regulating device 12 which is responsive to changes in ambient temperature and consists of a metal rod with a relatively high heat-expansion coefficient. The rod 12 is pivoted in the fixed bracket 28 and is connected with the balance 9 by the lever 13 and the connecting arm 30. Said lever 13 is pivoted at one end thereof in the fixed bracket 29 and said rod 12 is pivotally connected to said lever 13 intermediate the ends of said lever 12. The arm 30 is pivotally connected to lever 13 and balance 9 as shown.

When the ambient temperature drops the regulating device 12 contracts and turns the balance 9 somewhat clockwise, so that the gap between

the coils 6 and 8 is reduced. The primary leaky field of the transformer thus becomes smaller and a higher potential is induced in the secondary coil 6. This higher potential causes an increase of the current flow through the discharge lamps which increases the heat developed by the discharge in these lamps. The circuit is regulated in such manner that this increased heat of the discharge equals the increased heat 10 radiation caused by the drop in ambient temperature so that the metal vapor pressure in the discharge lamps always has the same value.

Instead of a regulating device comprising a solid metal element which exerts the necessary force, a liquid column is used, when desired. The change in the volume of the liquid when an ambient temperature change occurs is utilized to move the balance 9. The use of a liquid has the advantage that substances having an appreciably 20 greater expansion coefficient than the solid metals can be used.

The illuminating system illustrated in Fig. 2 is connected to the terminals 14 of a direct current source and comprises a number of linear 25 discharge lamps 15 which have thermionic electrodes and a gaseous filling comprising a metal vapor. An external resistance 16 is connected in series with these discharge lamps 15. Various 30 taps 17 on this resistance are connected with contacts 18 which are connected in pairs by the contacts 19 whereby the parts 20, 21 and 22 of the resistance 16 are short circuited. The contacts 19 are lifted by the magnet coils 23 whereby the short circuit of the above mentioned parts 35 of the resistance is broken. The coils 23 are connected at one end to one terminal of a battery 24 and at the other end to contact members 25 mounted in spaced positions along the glass tube 26 which contains an amount of mercury 40 27. This mercury is connected to the other terminal of the battery 24.

When the ambient temperature increases the

mercury rises in the tube 26. In doing this it touches the first contact member 25 and the left hand coil 23 is energized and lifts the contact 19 to open the short circuit of the resistance section 20 so that the resistance, which is connected in series with the discharge lamps, is increased. The current through the lamps and the heat developed by the discharge in the lamps is reduced so that the vapor pressure is unchanged. If the ambient temperature increases still further the coils 23 are energized in sequence and the short circuit of the resistance sections 21 and 22 is opened whereby the strength of the current through the discharge lamps is still farther reduced and the vapor pressure remains unchanged. 15

On alternating current operation, one can also use a choke coil as external impedance and change the size of this choke coil by the regulating device.

While we have shown and described and have 20 pointed out in the annexed claim certain novel features of the invention, it will be understood that various omissions, substitutions and changes in the forms and details of the device illustrated and in its use and operation may be made by 25 those skilled in the art without departing from the broad spirit and scope of the invention.

What we claim as new and desire to secure by Letters Patent of the United States is:—

An illuminating system comprising in combination, a plurality of electric discharge vapor lamps connected in series, a current source for said devices and a current regulator responsive to changes in ambient temperature connected in said system between said current source and said lamps, said current regulator comprising a thermal responsive means controlling a current variator means. 30
